United States Patent Office.

CORNELIUS WALSH AND JOSIAH WALSH, OF NEWARK, NEW JERSEY,
ASSIGNORS TO CORNELIUS WALSH.

Letters Patent No. 97,733, dated December 7, 1869.

IMPROVED FASTENING FOR TRAVELLING-BAGS.

The Schedule referred to in these Letters Patent and making part of the same.

We, CORNELIUS WALSH and JOSIAH WALSH, of Newark, in the county of Essex, and State of New Jersey, have invented an Improved Fastening for Travelling-Bags, and do hereby describe the same.

Nature and Objects of the Invention.

Our fastening is of the description usually employed at the ends of travelling-bags as additional or supplementary supports, and is so constructed as to open and close without rubbing the cover.

The invention consists in a novel combination and arrangement of parts in such a fastening.

Description of Drawings.

The accompanying drawings represent a pair of our improved fastenings applied to a bag-frame as side clasps—

Figure 1 being a perspective view of the frame and fastenings in an open position;

Figure 2, a partial end view, with the frame and fastenings closed; and

Figure 3, a transverse section at *z z*, fig. 2.

Similar marks of reference indicate like parts in the several figures.

General Description.

A A, in the drawings, represent the respective jaws of the frame;

a a, the hinges connecting the same; and

B, the band applied to the jaw A, to cover the joint, &c.

None of these parts require any special construction for the reception of the fastening forming the subject of this invention. Their presence, however, in some form, or their equivalent, is necessary for the application of the fastening to a bag.

The fastening in its preferred form is composed of a base plate or bracket, 1, a clasp, 2, and a button or stop, 3.

The bracket 1 is adapted for attachment by rivets, *b b*, or their equivalents, to the band B, or a similar part of the frame, and for the reception of the other parts, 2 3, of the fastening, being employed to support said parts.

The clasp 2 is of L-shape, consisting of two portions at right angles to each other, and is hinged at one extremity to the bracket 1, by a pivot 4, parallel with the base of said bracket and with its own bearing-face 5.

The fastening is applied so that the pivot 4 of the clasp shall be parallel with the surface with which it is to engage, and at such distance from the front edge of the top of the frame as to allow the clasp to close around it, (as indicated in fig. 3 of the drawings,) in which manner it operates.

It thus closes directly against the surface with which it is to engage, consequently without rubbing it. In opening, it moves directly away from the surface engaged. Its action may be compared to that of the hand in closing and holding the mouth of a bag.

It is provided outside of its pivot with a shoulder, 6, for the engagement of a button or stop, 3, to hold it in its closed position, which shoulder may be also so disposed as by engagement with the top of the bracket to form a positive limit to its retraction.

The button or stop 3 may be of any form presenting a retractable surface, 7, for the engagement of the shoulder 6 on the clasp 2. It is applied to the top of the bracket, and preferably pivoted at 8.

The engaging surfaces 6 7, of the clasp 2, and button or stop 3, are preferably made inclined, as represented.

The precise shape of the several parts is variable. They are each capable of receiving ornamentation. They may preferably be cast from brass.

In use, two of our fastenings as end clasps may be employed in connection with a central lock, as in the illustration represented, or one or more of them may be employed alone or in connection with one or more locks or other fastenings of any description.

Detached, the fastenings will of course form an article of manufacture and merchandise. When intended for end clasps, they may be made in pairs, as indicated, or have a uniform construction.

As a modification, the clasps might be hinged directly to the band of the frame.

Operation.

The mouth of the bag being closed and locked, the clasps 2 are pressed around against the face of the movable jaw A', and, being held there, the stops 3 are brought into position, supporting them. The stops being removed, the clasps may be turned back, releasing the movable jaw, and allowing the bag to be opened.

Claim.

We claim, as our invention—

A fastening for travelling-bags, composed of a bracket, 1, clasp 2, 4, 5, 6, and button or stop 3, 7, constructed and arranged to operate in the manner herein represented and described, for the purposes set forth.

CORNELIUS WALSH.
JOSIAH WALSH.
